UNITED STATES PATENT OFFICE.

PETER A. SOLEM, OF CINCINNATI, OHIO, ASSIGNOR TO J. A. FAY & EGAN COMPANY, OF CINCINNATI, OHIO, A CORPORATION OF WEST VIRGINIA.

WOOD-PLANING MACHINE.

1,079,032.

Specification of Letters Patent.

Patented Nov. 18, 1913.

Application filed February 1, 1913. Serial No. 745,696.

To all whom it may concern:

Be it known that I, PETER A. SOLEM, a citizen of the United States, residing at Cincinnati, in the county of Hamilton and State 5 of Ohio, have invented certain new and useful Improvements in Wood-Planing Machines, of which the following is a specification.

My invention relates to wood-planing machinery, and is principally applicable to wood-planing machinery employing a horizontally disposed cutter-head arranged to operate on the upper side of stock, whether said cutter-head is the sole cutter-head in the 15 machine, or other cutter-heads operating for instance on the bottom or on one or more edges of the stock, are employed.

It is the object of my invention to provide new and improved relation of means whereby 20 the chips caused by the cutter-head are removed; further to provide new and improved relation of means whereby the cutter-blades of the cutter-head may be jointed during operation of the machine; further to 25 provide a shaving-hood and jointing means for the cutter-head located in such relation to each other and to the chip-breaker as to permit simultaneous operation of all said means, and the invention will be further 30 readily understood from the following description and claims, and from the drawings, in which latter:

Figure 1 is a side elevation of my improved device showing so much of a wood-planing machine as is necessary to illustrate my invention. Fig. 2 is a vertical cross-section of the same taken on the line 2—2 of Fig. 4. Fig. 3 is a front view of the same. Fig. 4 is a top plan view of the same, partly 40 broken away; and Fig. 5 is a sectional detail of the clamping means for the cutter-head housing taken on the line 5—5 of Fig. 3.

I do not in this invention claim the positioning means for the cutter-head housing, 45 the same being claimed in a separate application, Serial No. 772598 filed June 9, 1913 divisional hereof, or the chip-breaker and its adjusting and controlling means, the same being claimed in a separate application, Serial No. 772110, filed June 6, 1913, divisional 50 hereof.

11 represents the main frame of the machine, on which there are standards 12 having guides 13 thereon. A cutter-head hous-

ing 14 has guideways 15 coöperating with 55 said guides and has movement up and down on said guides. These guideways preferably have a bottom wall 17 and an end wall 18, plates 19 being secured to the end walls 18 by bolts 20. The cutter-head housing is ad- 60 justed to elevation by means of screw-rods 25 threaded in nuts 26 in the housing and journaled and held longitudinally stationary in bearings 27 in the main frame, and have bevel-gears 28 fast thereon. 65

29 is a cross-shaft journaled in bearings 30 in the main frame. Bevel-gears 31 are fast on the cross-shaft and mesh with bevel-gears 28, the cross-shaft being provided with a squared end 32 arranged to be received in 70 a suitable socket-wrench for turning the same.

The cutter-head housing is clamped in ad- 75 justed position by clamp-screws 36 (see Fig. 5), journaled in bearings 37 in the plates 19 and threaded in bearings 38 in the bot- 80 tom wall 17, passing through slots 35 in the guides 13. A set-nut 39 and a jam-nut 40 are screwed about the outer threaded end 41 of each of the clamp-screws. The clamp- 85 screws are turned by arms 42 (see also Figs. 1, 3 and 4) having spline-connection with the clamp-screws. This spline-connection is shown accomplished by a key 43 in the clamp-screw received in a spline-groove 44 in the hub 45 of the arm 42.

The arms at the respective ends of the cutter-head housing are connected by links 46 having articulation with said arms at 47, arms 48 extending from the hubs 45, the 90 arms being connected by a link 49 articulated therewith by articulations 50. The arms 48 have hand-grips 51 thereon.

A cutter-head 55 is journaled in bearings 56 in the cutter-head housing or support. 95 It is arranged to carry suitable cutter-blades, instanced by the cutter-blades 57.

61 is a chip-breaker before the cut of the cutter-head, which may comprise a chip-breaker foot 62 adjustable on the body 63 100 of the chip-breaker toward and from the cutter-head. The foot has a toe 64. This adjustment is shown accomplished by pro- 105 viding a guideway 65 between the body and foot of the chip-breaker. (See Figs. 2 and 3.) A set-screw 66 at each end of the chip-breaker is adjustable in a threaded bearing 67 on a lug 68 on the foot 62 and is locked in

adjusted position by a lock-nut 69, the end of the set-screw bearing against a lug 70 on the body of the chip-breaker. The chip-breaker foot is clamped to its body by means 5 of clamp-screws 71 received through slots 72 in the body and threaded into threaded bearings 73 in said foot. Means hereinafter described are provided for limiting approach of the toe toward the cutter-head. The chip-breaker 10 has sliding connection at each end thereof with the cutter-head housing, shown in the form of guides 75 on the body of the chip-breaker slideable in guideways 76 in the housing, one wall of the said guideways being formed by plates 77 rigidly secured to the housing by bolts 78. The toe 64 of the chip-breaker is provided with a stock-contacted face 79 closely adjacent to its chip-breaking edge, parallel with the plane of the 15 feeding face of the stock-support 82 and with a forward end wall 80 parallel to the right line movement of the chip-breaker caused by the guides 75 and guideways 76. The chip-breaker foot has an upwardly 20 slanting stock contacted sole 81 arranged to be contacted by the end of stock having a wide range of varying thicknesses.

For the purpose of resiliently resisting rising movement of the chip-breaker, I provide 25 double-link yokes 91, 92, the double-link yoke 91 comprising the links 93 having a cross-piece 94 integral therewith. The double-link yoke 92 comprises the links 95 having a cross-piece 96 integral therewith 30 between the same at one end thereof. The double-link yoke 91 has bearings 97 at one end thereof, in which journal-bolts 98 are journaled, the journal-bolts having threaded connection in the bearings 99 of the body of 35 the chip-breaker. The double-link yoke 91 further has bearings 100 at its other end, in which journal-bolts 101 are journaled, these journal-bolts having threaded connection in the connected bearing 102 at one end of the 40 double-link yoke 92. The latter yoke further has bearings 103 at the other end thereof, through which a rod 104 extends, the rod further having support in the lugs 105 of the cutter-head housing.

50 111 is a pivoted cup in which a spring 112 is received, the cup being on a cross-piece 113 having trunnions 114 journaled in bearings 115 of the links 95. These trunnions are located nearer the pivotal connections of 55 the links 95 with the housing than the pivotal connections between the links 95 and 93, whereby a minimum of movement of compression and extension of the spring will be caused by the movement of the links 95 in 60 accommodating themselves to the changing positions of the chip-breaker.

A screw-rod 116 is threaded into a threaded bearing 117 in the cross-girt 118 of the cutter-head housing and is surrounded by 65 the spring 112 and has a cup 119 adjacent its

upper end adjustably positioned by a set-nut 120 and a lock-nut 121.

A set-screw 122 is threaded into a threaded bearing 123 in the yoke 92 and impinges the cross-girt 118 for limiting the downward 70 movement of the chip-breaker, and is locked in adjusted positions by a lock-nut 124.

Means are provided for sharpening or jointing the knives on the cutter-head while the same are rotating at full speed, so as to insure a smooth cut being taken off the stock. I have shown this accomplished by means of a block 130 of suitable material, which acts upon the cutting edges of the cutter-blades on the cutter-head during their rotation at full speed, this block of material, such as carborundum or other knife-sharpening substance, being moved lengthwise of the cutter-head during such rotation, it being understood that the cutter-blades have 80 been previously sharpened and approximately set for causing the cutting edges of the cutter-blades to swing in as true a circle as can ordinarily be effected by the usual setting and gaging mechanisms. The block 85 is fastened in a slide 131, being clamped in the channel 132 thereof, by a clamp-screw or screws 133. The slide is movable up and down in a guideway 134 of a carriage 135 by means of an adjusting screw 136 journaled in a bearing 137 on the slide and held 90 therein against endwise movement, and threaded into a bearing 138 on the carriage, a spring 139 being located around the adjusting screw between said bearings for 95 causing recession of the slide from the cutter-head as far as the adjustment of the parts will permit, whereby lost motion is taken out for causing the jointing block to be backed by positive stops, namely, the 100 screw and its bearings, and preventing further recession thereof during operation and preventing chattering of the block and consequently insuring that the cutting edges of the cutter-blades be jointed in true lines 105 at equal distances from the axis of rotation of the same and preventing any wavy or uneven action upon the cutting edges. The carriage 110 is slidable back and forth lengthwise of the cutter-head on a slide 140, secured to brackets 141 on the cutter-head housing, as by means of bolts 142 received through slots 143 in lugs 144 of said slide and threaded into the brackets 141, permitting 115 adjustment of the slide with relation to the axis of rotation of the cutter-head for taking up any wear and insuring accuracy of result. A rod 145 is preferably releasably secured to the carriage, as by means of a threaded connection 146, the rod having a 120 handle 147 thereon, by means of which it may be moved lengthwise of the slide during the jointing operation. The carriage may be moved to one end of the slide for bringing the same out of operative relation with 125 130

the cutter-head. It may be placed opposite one of the bearings of the cutter-head when not in use.

151 is a shaving-hood, which has a mouth 152, extending preferably across the width of the cutter-head, at one side of the cutter-head and located at one side of the jointing means just described. The mouth is arranged at that side of the cutter-head which 15 moves away from the surface of the stock being planed, instanced as the feed-in side of the cutter-head, for receiving the chips from that side of the cutter-head, and drawing in all the chips made by the cutter-head, 20 for preventing the passage of said chips to the jointing mechanism, the mouth preferably opening adjacent to the top of the bonnet 153 of the chip-breaker. The jointing device is located entirely outside the shaving-hood for permitting the operation of the jointing device without action upon or disarrangement of the hood, the jointing device being separated from the shavings passage of the shaving-hood by one of the walls of 25 said hood, while the hood is also removable away from the cutter-head. The action of the shaving-hood is to take the shavings from each individual blade before it reaches the jointing device, whereby no interruption 30 to the feeding of the board or stock through the machine need take place while jointing the knives. The shavings are removed by a current of air through the hood in the direction of the arrow e. The shaving-hood preferably opens at one side of the cutter-head, the jointing device being slidable at the other side thereof.

For conveniently mounting and permitting removal of the shaving-hood I provide 40 the same with a hook 155, which is received upon the rod 104, and with lugs 156, one of these lugs being at each end of the shaving-hood, and arranged to rest upon shelves 157 of the cutter-head housing, for positioning 45 the hood with relation to the housing and permitting the mouth of the hood to be arranged as close to the cutter-head as possible. The hood has telescoping connection 158 with the pipe 159 of the blower-system 50 for permitting ready movement of the hood up and down.

My improved device further provides ready means whereby the shaving-hood and the jointing device are located and operable 55 side by side about the cutter-head, each being independently movable, the mouth of the shaving-hood being further so arranged with relation to the chip-breaker as to permit right line movement of the chip-breaker with 60 relation to the cutter-head.

Having thus fully described by invention, what I claim as new and desire to secure by Letters Patent, is:

1. In a wood-planing machine, the combination with a rotary cutter-head provided

with cutter-blades, of a shaving-hood having a mouth and a jointing means for the cutting edges of said cutter-blades located side by side at said cutter-head, the wall of said shaving-hood being interposed between 70 the shavings-conducting channel in said shaving-hood and said jointing means.

2. In a wood-planing machine, the combination with an upper rotary cutter-head, of a chip-breaker therefor, a jointing attachment operable lengthwise of said cutter-head, and a shaving-hood having a mouth between said chip-breaker and jointing attachment, said mouth being removable 75 independently of said chip-breaker and jointing attachment.

3. In a wood-planing machine, the combination with an upper rotary cutter-head provided with cutter-blades, of a chip-breaker comprising a bonnet, a shaving-hood having a mouth opening at said bonnet, means for automatic movement of said bonnet with relation to said cutter-head, and a jointing means for the cutting edges of 85 said cutter-blades operable lengthwise of 90 said cutter-head alongside said mouth.

4. In a wood-planing machine, the combination with an upper rotary cutter-head, of a shaving-hood and jointing means located and simultaneously operable at said cutter-head, said shaving-hood and jointing means being independently movable.

5. In a wood-planing machine, the combination with an upper rotary cutter-head, of a shaving-hood, and a jointing attachment 95 located and operable side by side about the axis of rotation of said cutter-head, said shaving-hood and jointing attachment being independently movable.

6. In a wood-planing machine, the combination with an upper rotary cutter-head, of a chip-breaker therefor, a shaving-hood having a mouth opening adjacent to said chip-breaker, and a jointing attachment operable lengthwise of said cutter-head, said 105 chip-breaker, shaving-hood and jointing attachment being located simultaneously in operable positions side by side about the axis of rotation of said cutter-head.

7. In a wood-planing machine, the combination of a frame, an upper cutter-head housing, means for adjusting said housing up and down on said frame, a chip-breaker movably mounted on said housing, a shaving-hood supported on said housing, a jointing means supported by said housing and comprising a guideway substantially parallel to the axis of rotation of said cutter-head, and a jointing part movable lengthwise of said guideway, said chip-breaker, 110 shaving-hood and jointing means adjustable with said housing and located simultaneously in operable positions about said cutter-head.

8. In a wood-planing machine, the combi-

nation of a frame, an upper cutter-head housing adjustable up and down thereon, a cutter-head journaled in said housing, a chip-breaker, pressure means for said chip-breaker comprising links, a rod on said housing about which said links are pivoted, a shaving-hood having an opening adjacent to said chip-breaker at one side of said cutter-head, and means for removably supporting said shaving-hood on said rod.

9. In a wood-planing machine, the combination of a frame, an upper cutter-head housing adjustable up and down thereon, a cutter-head journaled in said housing, a chip-breaker at one side of said cutter-head, a jointing means comprising a guideway at the other side of said cutter-head, said jointing means comprising a jointing part movable lengthwise of said guideway during rotation of said cutter-head, and a shaving-hood operatively located between said jointing part and chip-breaker during operative relations of said jointing part and chip-breaker with relation to said cutter-head.

10. In a wood-planing machine, the combination of a supporting part comprising a cross-girt as a rigid part thereof, an upper cutter-head supported on said supporting part at the rear of said cross-girt, a jointing

means for said cutter-head comprising a jointing part movable lengthwise of the axis of rotation of said cutter-head, a chip-breaker on said housing extending under said cross-girt from the front, and a shaving-hood on said housing extending under said cross-girt from the rear between said jointing means and cross-girt and directed toward said chip-breaker.

11. In a wood-planing machine, the combination of a supporting part comprising a cross-girt as a rigid part thereof, an upper rotary cutter-head supported on said supporting part at the rear of said cross-girt, a jointing means comprising a jointing part operable lengthwise of the axis of rotation of said cutter-head, a shaving-hood located between said jointing means and cross-girt, and a chip-breaker for said cutter-head comprising a bonnet located within the longitudinal projection of said shaving-hood.

In testimony whereof, I have hereunto signed my name in the presence of two subscribing witnesses.

PETER A. SOLEM.
